UNITED STATES PATENT OFFICE.

FRANK H. ALFRED AND PAUL CHIPMAN, OF DETROIT, MICHIGAN.

RAILWAY-ROADBED CONSTRUCTION.

Application filed June 16, 1927. Serial No. 199,307.

This invention relates generally to railway road-bed construction and consists of certain novel features of construction, combinations and arrangements of parts as will be herein-
5 after more fully described and particularly pointed out in the appended claims.

In the past, heavier rails with stronger fastenings of improved pattern have been used, the depth of the ballast has been increased, and the ties have been placed closer together to keep pace with the increase in the weight of equipment and the volume of traffic. On account of its adaptability to the varying conditions incident to the growth of 10 the railway systems, such as an unseasoned road-bed and frequent changes in line and grade, no other type of track could have served the purpose as well on the score of efficiency or of economy.

20 But on most of the railroads in this country a different set of conditions is now encountered. Traffic routes have become fixed. Few changes of line or grade which involve any considerable mileage are contemplated. Embankments have become seasoned, and for the most part show no further settlement. Wheel loads are approaching the maximum which is permissible, unless steel rails can be made both harder and tougher than at present. 25 The increasing cost of ties is only partially offset by the longer life obtained by treatment. Suitable ballast is increasingly more expensive and track labor is becoming scarcer and, measured in performance, more costly. 30 Therefore the time has now arrived when a more permanent roadbed, i. e. a track structure in which wear and deterioration are confined as far as possible to the rails, is desirable. However, the requirements for such 35 a track structure are most exacting, as there are many conditions to be considered.

Such a structure must be wide enough and strong enough to distribute the load over such an area that the bearing power of the sub-grade will not be exceeded. Allowance must be made for impact, for lack of uniformity in the support given by the sub-grade, and for the present tendency toward heavier loading. Temperature stresses must be taken into consideration, and protection of the bed material such as concrete under the rail from disintegration due to repeated shock from the passing loads seems desirable.

The method of attaching the rails should 55 permit of easy placement and removal.

Methods and types of construction must be such that the rails, when laid in their prepared places, will have perfect surface and alignment. However the design should be such as to permit minor adjustments of elevation by shimming as occasional slight settlement may be looked for even in seasoned fills, and changes in traffic conditions may make a change in the super-elevation of curves desirable. Ease of insulation is another feature that must not be overlooked. As there will be occasional situations where it will be desirable to retain the present type of track, any design should permit an easy and practicable connection of the two types of construction.

With the present invention, the features just mentioned have all been considered. As a result we have provided a roadbed that is preferably formed of a series of reinforced 65 concrete slabs arranged end to end and having smooth plane top surfaces on which the rails are mounted.

In the accompanying drawings:

Figure 1 is a fragmentary top plan view of 80 a roadbed construction embodying my invention.

Figure 2 is a side elevation thereof.

Figure 3 is a sectional view taken on the line 3—3 of Figure 1.

Figure 4 is a side elevation of the longitudinal reinforcing frame of the roadbed.

Figure 5 is an enlarged fragmentary detail elevation of one view of the construction shown in Figure 4.

Figure 6 is a sectional view taken on the line 6—6 of Figure 5 and showing a rail in dotted lines upon the frame.

Figure 7 is a fragmentary vertical sectional view through the upper chord of one of the trusses and showing the rail in dotted lines applied thereto.

Figure 7^A is a side elevation of the stirrup and rail clip and showing a rail applied thereto.

Figure 8 is a detail view of one of the cross braces.

Figure 9 is a detail view of one of the tie rods.

Figure 10 is a detail side elevation of one 105 of the rail clips.

Figure 11 is a top plan view of the construction shown in Figure 10.

Figure 12 is a view similar to Figure 7 but showing a slightly modified construction. 110

Figure 13 is a view similar to Figure 3 but showing a slightly modified form of construction.

Referring now to the drawings, 1 is a slab 5 constituting one section of a roadbed embodying our invention. As shown this slab comprises a mass 2 of concrete that may have any suitable dimensions such as ten feet wide, eighteen inches thick and is preferably equal 10 in length to the length of the rails 3, for instance 39 feet long. Preferably this mass 2 of concrete is cast upon a thin layer 4 of fine sand which in turn, is located upon ballast 5 that has been grouted. Embedded in this 15 mass 2 of concrete is a metal frame 6 and a lattice work 7 of longitudinally and transversely extending bars 8 and 9 respectively. As shown the frame 6 preferably comprises a pair of parallel longitudinally extending 20 trusses 10 and 11, and the longitudinally spaced transversely extending braces and tie rods 12 and 13 respectively. Preferably each truss consists of a pair of vertically spaced chord members 14 and 15, longitudinally 25 spaced uprights or struts 16, end diagonal brace members 17 and 18 respectively, and intermediate diagonal brace members 19 and 20. In each instance the lower chord member 14 is horizontally disposed and consists of parallel 30 horizontal bars 21 and 22 respectively which are preferably arranged with the vertical webs thereof innermost and the horizontal webs thereof lowermost. The upper chord member 15 is also horizontally disposed, in fact substantially parallel to the lower chord member, and preferably consists of vertically disposed parallel plates 23 and 24 respectively. If desired such plates may be provided throughout their length with 35 spaced openings 15' for receiving portions of the concrete so as to insure a rigid connection between the parts. The uprights or struts 16 are preferably vertically arranged and are located between the parallel plates 23 and 24 of the upper chord and between the parallel bars 21 and 22 of the lower chord. Preferably these struts 16 are channel-shape and are riveted to the bars 21 and 22 respectively of the lower chord member and to the 40 plates 23 and 24 respectively of the upper chord member. To provide an efficient construction the upper ends of such struts 16 preferably terminate flush with the upper edges of the plates 23 and 24, while the lower 45 ends of such struts terminate below the lower chord member 14, and with certain exceptions, rest upon supporting stakes 25 driven into the ballast 5. The end diagonal members 17 and 18 are also channel-shape in form and are riveted at their opposite ends to the 50 bars 21 and 22 respectively of the lower chord member and to the plates 23 and 24 respectively of the upper chord member. Preferably these end diagonal members incline inwardly 55 from the upper chord member 15 to the lower

chord member 14 as shown in Figure 4 of the drawing. The intermediate chord members 19 and 20 are also channel-shape in form and are riveted at their opposite ends to the bars 21 and 22 respectively of the lower chord member and to the plates 23 and 24 respectively of the upper chord member. Preferably these diagonal members 19 and 20 diverge downwardly from the upper chord member 15 to the lower chord member 14 and 60 extend between certain of the spaced uprights or struts 16. As shown in Figure 8 each brace 12 comprises two bars 26 and 27 respectively which are rigidly secured together intermediate their ends by the spaced rivets 65 28 and 29 respectively. Preferably the lower bar 26 is substantially flat and is provided at its opposite ends with depending lugs or flanges 30 and 31 respectively which are preferably bolted to the struts 16 at points preferably immediately below the lower chord members 14 of the trusses. The upper bar 27 is substantially U-shape in form and is provided at its opposite ends with the upstanding lugs or flanges 32 and 33 respectively 70 which are bolted to the uprights 16 preferably at points immediately below the upper chord members 15. Preferably each brace 12 is accurately constructed so that the length thereof is substantially equal to the true gauge 75 desired between the uprights of the laterally spaced trusses. However, should any inaccuracies occur adjustments of the bolts and nuts constituting the securing means therefor may be readily made to compensate for 80 such irregularities. The tie rods 13 are preferably used to adjust the laterally spaced trusses to the proper positions and are adjustably connected to certain of the uprights 85 16 of such trusses, preferably at points immediately below the upper chord members 15 thereof. Any suitable means such as the nuts 34 and 35 respectively threadedly engaging the tie rod 13 at the opposite ends thereof 90 may be used to accomplish the adjustments 95 desired. As shown the longitudinally and transversely extending bars 8 and 9 of the lattice work 7 are arranged in rows between the chord members 14 and 15 of the trusses. Preferably the transverse bars 9 are arranged 100 in parallel relation to each other and terminate short of the side edges of the concrete mass 2, while the longitudinal bars 8 are also arranged in parallel relation to each other and terminate short of the ends of the concrete mass 2. Where cross braces and tie rods occur other transverse reinforcements 105 such as the bars 9 are omitted.

In the present instance the rails 3 are held by clips 40 which are bolted to lateral extensions 41 of the stirrups 42 embracing the upper chord members 15 of the trusses. As shown, the lateral extensions 41 of the stirrups 42 have downwardly and outwardly inclined portions 43 which are embedded in 110

the concrete and form a rigid anchorage therefor. Preferably the bolts 44 used to attach the clips 40 to the extensions 41 are arranged with the heads thereof uppermost 5 and are screwed into nuts 45 which in turn are inserted through recesses 45' provided for that purpose beneath the stirrup extensions 41. As shown these recesses 45' are only slightly wider than the nuts 45, thus said nuts 10 are prevented from turning. This arrangement tends to lessen the danger of injury to the bolts in case of derailment, and permits their replacement if injury should occur, or the substitution of a longer bolt in case slight 15 shimming is desirable. Nut locks can be used under the bolt heads if desired.

Preferably our roadbed would be formed of a series of slabs 1 and the latter would be arranged end to end with tongue and 20 groove connections therebetween. For instance one end of each slab would be provided with a transversely extending tongue 1', while the opposite end of such slab would be provided with a transversely extending groove 25 1'' (see Fig. 2). Thus when the slabs are assembled the tongue and groove arrangement would effectively prevent sagging of said slabs at the joints.

It is also desirable to use fibre cushions for 30 the rails and to insulate the metal parts such as the bolts 44 etc. from adjacent parts such as the clips 40, rails 3, and stirrups 42. For instance fibre plates 3' are placed between the concrete slabs and the bases of the rails 35 3 to cushion the latter. Fibre sleeves 44' and washers 44'' are also preferably used to insulate the bolts 44 from the clips 40. The latter are also cushioned by the fibre plates 40' on the concrete slabs and are insulated from 40 the rails 3 by the upturned plate extensions 40'' which overlap and rest on the upper faces of the bases of said rails 3.

In Figure 12 we have shown a slight modification in which the rail clips 40 are bolted 45 to the lateral portions 50 and 51 respectively of stirrup sections, and the latter are in turn bolted to opposite sides of the plates 23 and 24 respectively of the upper chord member.

In Figure 13 we have shown another modification in which the parallel plates 60 and 50 61 respectively of the upper chord members of the trusses are provided at their upper edges with outwardly extending lateral flanges 62 and 63 respectively upon which the rails 3 are mounted. With this construction the rail clips 40 are bolted to the flanges 62 and 63 respectively, and the stirrups are dispensed with entirely.

Thus, from the foregoing description it 60 will be apparent that the parallel plates of the upper chord members serve a four-fold purpose, i. e. (1) to distribute the load and impact over a greater area of concrete; (2) to protect the concrete from shock and possible 65 disintegration due to direct contact with the

rail; (3) to afford a means of attaching the rail; (4) to insure a seating for the rail which is absolutely true as to line and surface. In addition they form a guide for striking off the concrete surface in finishing, such plates 70 also form the upper chord of a light truss, the lower chord of which serves as a part of the longitudinal reinforcement. The vertical members of this truss serve to anchor the rail seats in the concrete and are extended below the lower chord so that they may rest upon the stakes 25 which are driven accurately to the elevation of the sub-grade. Preferably these trusses would be shop made, and the bracing and riveting need only be of sufficient strength to prevent distortion while 75 handling. When set in place these trusses are maintained in proper relation to each other by the adjustable tie rods 13 and also by the cross braces 12. Thus this frame work 80 can be set accurately in place and will remain undisturbed while the concrete is being cast upon the same. It will also serve to transmit the loads into the mass of concrete. With such a design, the rails no longer function 85 as beams. A wearing surface and a base for bearing and attachment are all that need be provided, so that a much lighter rail may be used than at present.

Thorough drainage is essential. On fills 90 made of sand no artificial drainage would be necessary, but on other fills it should be taken care of by tile drains 71 just beyond the edges of the slab, with frequent outlets to the side of the embankment. In cuts the drains should 100 be placed deeper and under the cut ditches, in order to prevent ground water from reaching the track. The proper functioning of these drains is a very important matter and they should be of ample size and have good outlet 105 facilities.

Conduits 72 for carrying all wiring, such as telegraph, telephone, block signals and train control, can be placed in the center of the slab as shown in the cross section, or can 110 be placed elsewhere in the section if desired.

If desired straight lengths 73 of pipe may be embedded in the slabs so that grout or sand may be placed beneath the slabs, and are provided at their upper ends with removable 115 closures such as plugs 74 which are accessible at the top of the slabs.

While it is believed that from the foregoing description, the nature and advantage of our invention will be readily apparent, we 120 desire to have it understood that we do not limit ourselves to what is herein shown and described and that such changes may be resorted to when desired as fall within the scope of what is claimed.

What we claim as our invention is:

1. In a railway roadbed, the combination with a track including a pair of laterally spaced rails, and a foundation, of intermediate supporting means for said rails includ- 130

ing a mass of concrete upon said foundation and constituting a bearing or seat for said rails, and reinforcing means for said concrete including a pair of trusses embedded in 5 the mass in substantial vertical alignment with said rails, the height of each truss being substantially equal to the depth or thickness of said mass whereby portions of said trusses constitute struts between said 10 foundation and rails.

2. In a railway roadbed, the combination with a track including laterally spaced rails, and a foundation, of an intermediate support for said rails including a mass of concrete on 15 the foundation constituting a bearing or seat for said rails, and means for permitting grout to be placed between said foundation and mass including a tubular element extending through the mass with the opposite ends 20 thereof adjacent to the upper and lower surface of said mass, and a closure for the upper end of said tubular element accessible from the top of said mass.

3. In a railway roadbed, the combination 25 with a track including a pair of laterally spaced rails, and a foundation, of stakes in said foundation, an intermediate support for said rails including a slab of concrete on said foundation and constituting a bearing or seat 30 for said rails, and reinforcing means for said slab including truss members embedded in said concrete beneath said rails and having portions resting upon said stakes.

4. In a railway roadbed, the combination 35 with a track including a pair of laterally spaced rails, of supporting means therefor including a slab of concrete having smooth plane top surfaces constituting bearings or seats for said rails, the width of said slab 40 exceeding the distance between the rails, and the depth of said slab exceeding the depth of said rails, and reinforcements of said slab including trusses embedded in said slab beneath said rails and disposed in substantial 45 vertical alignment therewith, and braces embedded in and extending transversely of said slab connected to said truss.

5. In a railway roadbed, the combination 50 with a track including a pair of laterally spaced rails, of supporting means therefor including a mass of concrete constituting a bearing or seat for said rails, and reinforcing means for said concrete including laterally spaced trusses embedded in said mass in 55 substantial vertical alignment with said rails, connections between said trusses, reinforcing bars extending longitudinally of said mass, and cooperating bars extending transversely of said mass.

6. In a railway roadbed, a slab of concrete 60 having laterally spaced smooth plane top surfaces, reinforcements for said concrete including laterally spaced trusses embedded in and extending longitudinally of said slab,

the upper chord member of each truss being 65 horizontally disposed and having a pair of vertically arranged substantially parallel plates with the upper edges of said plates substantially flush with the top plan surfaces of said slab, and track rails mounted upon the 70 upper edges of said plates.

7. In a railway roadbed, the combination with a track including a pair of laterally spaced rails, of supporting means therefor including a slab of concrete constituting a 75 bearing or seat for said rails, reinforcing means for said slab including substantially parallel plates embedded in and extending longitudinally of said slab so as to receive the compression stresses of said rails, and 80 anchorage means for said rails including means projecting laterally from said plates, and clips engaging said rails and detachably secured to said laterally extending means.

8. In a railway roadbed, the combination 85 with a track including a pair of laterally spaced rails, of supporting means therefor including a mass of concrete constituting a seat for said rails, trusses embedded in the mass of concrete in substantial vertical 90 alignment with said rails and having chord members arranged substantially flush with the top surface of said mass and secured to said rails, and braces extending between 95 and secured to said trusses.

9. In a railway roadbed, the combination 100 with a track including a pair of spaced rails, of supporting means therefor including a mass of concrete, a substantially horizontally disposed frame work embedded in said concrete adjacent the bottom surface thereof, trusses also embedded in said concrete in substantial vertical alignment with said rails constituting seats therefor and secured at the lower ends to said frame work, and a brace 105 extending between said trusses secured intermediate the ends to said frame work and at the ends thereof to said trusses.

10. In a railway roadbed, the combination 110 with a track including a pair of spaced rails, of supporting means therefor including a mass of concrete, trusses embedded in said concrete, members secured to said trusses and also embedded in said concrete, said members having portions thereof lying substantially 115 flush with the upper surface of said concrete, and members secured to the portions aforesaid and engageable with said rails for securing the same in place.

11. In a railway roadbed, the combination 120 with a track including a pair of spaced rails, of supporting means therefor including a mass of concrete, trusses embedded in said concrete having chord members arranged substantially flush with the upper surface of said concrete in substantially vertical alignment with the rails, members secured to said chords having portions also embedded in said con- 125

crete, and clips secured to said members and engageable with the rails for securing the same in place.

12. In a railway roadbed, the combination 5 with a track including a pair of spaced rails, of supporting means therefor including a mass of concrete, trusses embedded in said concrete having chords arranged substantially flush with the upper surface of the concrete and in substantial vertical alignment 10 with the rails, members secured to said chords having laterally projecting portions terminating in depending projections also embedded in said concrete, and clips detachably 15 secured to said lateral projections and engageable with said rails for securing the same in place.

13. In a railway roadbed, the combination with a track including a pair of spaced rails, 20 of supporting means therefore including a mass of concrete, trusses embedded in the mass of concrete having laterally spaced longitudinally extending plates constituting chord members, elements secured to the said 25 plates having portions thereof arranged flush with the top surface of the concrete

and having other portions embedded within the said concrete, and means for securing the rails to said elements.

14. In a railway roadbed, the combination 30 with a track including laterally spaced rails and a foundation, of an intermediate support for said rails including a mass of concrete on the foundation constituting a bearing or seat for said rails and having a width exceeding 35 the distance between the laterally spaced rails, one end of said mass being provided with a transversely extending tongue and the other end of said mass being provided with a transversely extending groove whereby when 40 corresponding masses of concrete are arranged end to end with the groove of one mass receiving a tongue of another mass, the transversely extending tongue and groove arrangement would effectively prevent sagging of 45 said masses at the joints or meeting edges therebetween.

In testimony whereof we affix our signatures.

FRANK H. ALFRED.
PAUL CHIPMAN.
